SYSTEM OF FORMING SHEET MATERIAL

I. Lawrence Lesavoy, Allentown, Pa.

Application July 3, 1945, Serial No. 603,043

4 Claims. (Cl. 18—1)

1

This invention relates to a system of forming sheet material—more particularly to apparatus for rolling plastic or metal sheets containing raised ribs, beads or lengths of superimposed material.

In the fabrication of continuous lengths of sheet material by means of calender rolls, longitudinal beads can be formed through the use of coating circumferential grooves on the sheet-forming rolls. This method has the limitation that only relatively little thickness can be added for the formation of the bead, if conventional known methods are employed. It is accordingly within the contemplation of my invention to provide a system of rolling sheet material that will enable ribs, beads or laminated sections, both thick and thin, to be readily and conveniently joined to the sheet while it is being formed by a calender roll process.

Another object of this invention is to enable lengths or sections of different materials or colors to be added to sheet material during the rolling thereof, whereby reinforced or aesthetically attractive sheets are produced.

And it is within the contemplation of this invention to accomplish the aforesaid objectives by means of a relatively simple and continuously operated system.

Other objects, features and advantages will appear from the drawings and the description hereinafter given.

Referring to the drawings,

Figure 1 is a perspective view showing the apparatus of my invention for making a plastic sheet with beaded lateral edges.

Figure 2 is a perspective view of a heating cage adapted for use within a roller of Figure 1.

Figure 3 is a fragmentary longitudinal section taken along line 3—3 of Figure 1.

Figure 4 is a transverse section of Figure 1 taken substantially along line 4—4.

Figure 5 is an enlarged fragmentary perspective of a portion of the sheet of Figure 1, showing a beaded edge.

Figure 6 is an enlarged fragmentary perspective of another form of sheet adapted for fabrication with the apparatus of this invention, showing an undercut bead.

Figure 7 is a fragmentary horizontal axial section through two coating rollers, substantially like those shown in Figure 1, adapted to produce the sheet construction of Figure 6.

Figure 8 is a fragmentary perspective of a portion of the apparatus of Figure 1, but showing a

2

guide bar adapted to operatively receive extruded rods to form the beads of Figure 6, and

Figure 9 is a fragmentary perspective of another form of sheet construction adapted to be fabricated by the method of this invention.

Figures 1 to 5 disclose an apparatus for rolling plastic sheets according to one form of my invention—the particular embodiment shown being a system for beading the lateral edges of the rolled sheet.

The apparatus includes a hopper 15 for the semi-fluid plastic material 19 out of which a web of sheeting is to be formed, the outlet 16 of the hopper being disposed above the calender rollers 17 and 18. These rollers are adapted to engage therebetween the said plastic material fed by the hopper, pressing such material into a sheet 20 and directing said sheet to conveyor 21. The conveyor and the said rollers are actuated by any known means which are not herein shown because they are well-known in the art. The portion of the apparatus hereinabove described is substantially in accordance with conventional practice.

Above the said hopper 15 are the auxiliary feed rolls 22 which operatively receive therebetween the two extruded plastic rods 23 and 24, said rods emerging from outlets 44 and 45 of the extrusion apparatus 25. Said apparatus may consist of any known conventional method of extruding plastic material, and is accordingly not herein set forth in detail. The said feed rolls 22, which are actuated by means not herein shown, guide extruded rods 23 and 24 towards the hopper to form beaded edges, as will more fully hereinafter appear.

Although in the embodiment herein shown an extrusion apparatus is associated with the rolling apparatus, the invention is not limited to such a combination, inasmuch as pre-fabricated rods 23 and 24 may be employed within the scope of my invention.

The said hopper 15 is provided with a guide bar 26, having two holes 27 and 28 shaped to conform with the extruded rods 23 and 24 and adapted to slidably receive said rods during their downward movement toward outlet 16. The said holes 27 and 28 are spaced so as to correspond dimensionally with the circumferential grooves 29 and 30 on roller 17. In the preferred construction of this invention, said guide bar 26 is removable, so that it may be replaced by another guide bar containing holes of a different configuration to conform with the cross-sections of differently shaped extruded rods.

The said circumferential grooves 29 and 30 on roller 17 are so proportioned as to be able to ac-

commodate the extruded rods as they pass therethrough, the rollers being sufficiently spaced apart as to permit the sheet 20 to be in contiguous relation to rods 23 and 24.

The said rollers 17 and 18 are internally heated, in a manner to be hereinafter set forth, the heat being applied at the region of the grooves. The arrangement is such that during the downward passage of the rods and the sheet, heat is applied at the points of contact 31a of the rods and sheet, whereby these parts are fused together. This action is possible because the sheet is still in a semi-plastic state—the heat and pressure of the rollers at the point of fusion augmenting the sealing effect to form a fusion joint.

The apparatus for providing localized heat in the calender rolls consists, in the embodiment illustrated, of the cage 31 comprising an arrangement of tubes and heating elements in predetermined positions. In the particular design illustrated, the cage contains two tubular end coils 32 and 33 joined by transverse tubular rods 34. Electric heating elements 35 and 36 are disposed within the said end coils—and although the other coils are hollow and empty in the particular form shown, it is within the contemplation of the invention to employ suitable heating elements in any of the other tubular members 34 when required to suit a particular case.

The said cage 31 is disposed within roller 17, with the end coils 35 and 36 in the region of the grooves 29 and 30. One terminal of heating element 35 is electrically connected by conductor 36 to the armature ring 37 fixedly mounted on shaft 38, the ring of insulation 40 electrically separating the armature from said shaft and the roller 17 proper. The other end 43 of the heating element 35 is grounded to the roller 17. In frictional engagement with the armature 37 is the brush 41, which is electrically connected to a source of electrical energy 42. In the particular embodiment illustrated, the two heating elements 35 and 36 are connected in parallel, although if desired they may be connected in series.

For rolling a continuous sheet to which is fused an extruded bead of predetermined undercut cross-section, the apparatus disclosed in Figures 7 and 8 are employed—this being substantially similar to the method hereinabove set forth, with certain modifications. If it is to be assumed that the sheet 44 (see Figure 6) is to have superimposed thereupon the undercut bead 45, extruded rods 45a and 45b are employed (Figure 8), said rods being shaped like the said bead 45. The said rods 45a and 45b are operatively fed towards the hopper 15 by any known methods—and are directed through the guide bar 26a, slidably associated with the hopper substantially in the manner of the first-described form of my invention. The said guide bar 26a contains apertures 46 and 47 shaped to conform to the cross-section of the said rods 45a and 45b and proportioned to slidably receive these rods.

By referring to Figure 7 it will be seen that the two rollers 48 and 49 are adapted to receive therebetween the sheet 44. The roller 48 is also provided with a circumferential groove 50 adapted to accommodate one of the extruded rods—said roller 48 containing at the opposite end another circumferential groove like 50 for operatively accommodating the other of the extruded rods. In the operation of this apparatus, the extruded rods, such as 45a, are so fed towards the rollers that the undercut portion 51 is disposed out-

wardly, whereby such portion is brought into facing relation with the sheet 44.

The roller 48 also contains therein heating means similar to that hereinabove described, the heating element 35 being disposed in the region of circumferential groove 50. The arrangement is such that the undercut rod 45a is fused to the sheet 44 to produce a construction substantially like that shown in Figure 6.

It is apparent that by replacing the guide bar 26a with another one containing differently shaped apertures, different types of beads, including those of different undercut configurations, can be operatively applied to flat sheets in accordance with the method of this invention. The removal of the guide bars can readily be effected through handle 52. It is also apparent that instead of a bead-like member 45, a flat member 53 can be attached to the sheet 44 (Figure 9) in accordance with the method of this invention.

It is understood that other additional forms and modifications of the apparatus constituting this invention can be employed beyond and in addition to those hereinbefore described, all within the scope of the appended claims.

I claim:

1. In an apparatus for rolling a continuous sheet of plastic material with a longitudinal extruded bead superimposed thereon, a pair of 30 coacting rollers, a hopper thereabove for containing the material to be rolled in semi-plastic condition, said hopper having an outlet in feeding relation to said rollers, extruding means for forming a rod of said bead material, a guide bar 35 associated with said hopper and containing an aperture shaped to substantially conform with the cross-section of the rod and proportioned to slidably receive the rod, roller means interposed between the extruding means and the guide bar 40 for directing the extruded rod through said aperture and said hopper outlet to the said coacting rollers, one of said rollers containing a circumferentially grooved portion for operatively receiving therein said rod, the said rollers being shaped 45 to operatively accommodate therebetween said rod and said sheet material in contiguous relation, and heating means within one of said rollers and positioned adjacent said grooved portion, whereby the rod and sheet materials will be fused 50 together at their region of contact while passing through the rollers.

2. In an apparatus for rolling a continuous sheet of plastic material with a longitudinal extruded bead superimposed thereon, a pair of 55 coacting rollers, a hopper thereabove for containing the material to be rolled in semi-plastic condition, said hopper having an outlet in feeding relation to said rollers, means to feed to the rollers an extruded rod of the bead material, said 60 means including a guide bar associated with said hopper and containing an aperture shaped to substantially conform with the cross-section of the rod and proportioned to slidably receive the rod, said bar being in removable relation to the hopper whereby it can be replaced with another selected guide bar, the rollers being shaped to operatively accommodate therebetween said rod and the said sheet in contiguous relation, and heating means on one of said rollers and positioned adjacent the regions of contact of said 70 sheet and rod while passing through the rollers, whereby the rod will be fused to the sheet.

3. In an apparatus for rolling a continuous sheet of plastic material with an extruded bead of predetermined undercut cross-section super-

imposed thereon, a pair of coating rollers, a hopper thereabove for containing the material to be rolled, said hopper having an outlet in feeding relation to said rollers, means to feed to the rollers an extruded rod shaped to conform to the undercut bead, said means including a guide bar disposed within and extending across the hopper and containing an aperture shaped to substantially conform with the cross-section of the extruded rod and proportioned to slidably receive the rod, the rollers being shaped to operatively accommodate therebetween the rod and said sheet in contiguous relation, one of the said rollers containing a circumferential groove adapted to receive the said extruded rod with the undercut portion radially outwardly disposed with respect to the grooved roller, whereby such portion will be brought into operative contact with the sheet adjacent the other roller, and heating means at least on one roller and positioned adjacent the regions of contact of said sheet and rod while passing through the rollers whereby the rod will be fused to the sheet.

4. In an apparatus for rolling a continuous sheet of plastic material with a longitudinal bead superimposed thereon, a pair of coating rollers, a hopper thereabove for containing the material to be rolled in semi-plastic condition, said hopper having an outlet in feeding relation

to said rollers, means to feed to the rollers a rod of the bead material, said means including a guide bar containing an aperture shaped to substantially conform with the cross-section of the rod and proportioned to slidably receive the rod, the rollers being shaped to operatively accommodate therebetween said rod and the said sheet in contiguous relation, and heating means on one of said rollers and positioned adjacent the regions of contact of said sheet and rod while passing through the rollers, whereby the rod will be fused to the sheet.
